PACKAGING APPARATUS

Jay Tamassy, New York, N. Y., assignor to Jacob M. Hauser, doing business as Hauser Tea Bag Co., New York, N. Y.

Application April 8, 1939, Serial No. 266,739

11 Claims. (Cl. 226—56)

This invention relates to packaging apparatus and more specifically to apparatus for packaging bags which have tags attached.

In general, it is an object of the invention to provide a device of the character described which will efficiently perform the purposes for which it is intended, which is simple and economical of construction, which can be expeditiously, conveniently and safely manipulated, and which can be readily manufactured and assembled.

Another object of the invention is to provide a device which wraps a plurality of bags and tags, each bag with its own tag being enclosed in an outer wrapping, i. e., which prevents a tag which is connected to one bag from being wrapped with another bag; to provide such a device which utilizes the force of gravity to assist in accomplishing the particular result desired.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is a perspective view of a device embodying one form of the invention;

Fig. 2 is a cross-sectional view, in elevation, of a portion of the device shown in Fig. 1;

Fig. 3 is a view of the bag and tag separating elements; and

Fig. 4 is a view of the bag propelling element.

Certain materials such as tea, etc., are often enclosed in small cloth bags with a tag connected by a string or the like to the bag. The tag may have information printed on it regarding the maker, the grade of material, etc. It is sometimes desired, for various reasons, to enclose the bag and tag in a protective wrapping which may be of coated Cellophane or other like sheet material. One general method of wrapping is to introduce, one after another, the bags with their respective connected tags between strips of Cellophane and to seal off the Cellophane around each successive bag with its tag. It has been found that frequently the tag connected to one bag would become positioned near the preceding or succeeding bag with the result that the wrong tag has been sealed in a bag. The shearing

means which separate the successive wrapped bags has cut the string leading from the tag in one package to its proper bag in the next package. When the customer opened the packages, a loose tag would fall out or there might be no tag at all. The present invention contemplates a device for overcoming this and other difficulties heretofore known.

In the drawings, 10 denotes generally means for successively supplying objects such as bags, 10 etc., which are connected to tags. 12 denotes generally mechanism for spacing each tag from its bag. 14 indicates mechanism for bringing each bag and tag together again and 16 indicates generally the means for successively wrapping 16 together each bag with its own tag.

The bag-supplying means may be of any convenient form, that shown being an endless conveyor 18 having hoppers 20 attached thereto which each dump a bag and tag into hopper 22. 20 Grille means are provided in the hopper of such dimensions that they prevent the passage of a bag but do not prevent the dropping through the grille of the tag. Gravity normally pulls the tag through the grille and thus spaces the bag and 25 tag.

The grille means may take various forms, that shown being a pair of multiple tined forks 24. Each comprises a rotatable rod 26 to which the spaced tines 28 are attached. The rods are horizontally parallel and the tines extend toward each other, preferably downward. The material may be intercalated, if desired. Means described below are provided for rotating the rods and spacing the ends of the tines so that a bag may fall therethrough and down through the bottom of the hoppers to be caught between the vertical, spaced, parallel portions of endless belts 30. The distance between these portions is such that a bag does not fall through between those portions 40 but is carried along downward by, and in contact with, them.

As the bag passes downward, it is preceded by its depending tag. A propelling finger 32 is positioned toward the end of the travel of the bag 45 between the belts 30. Mechanical means described below are timed to cause the finger 32 to enter the space between the belts and knock the bag, which is present at that time, downward with increased velocity so that it overtakes its 50 own tag and falls, with it, between the wrapping wheels 34.

The wheels 34 each have two end rims 36 which are separated from the two similar rims of the other wheel only by the thickness of two 55

webs 38 of the packaging or wrapping material. These webs are brought from suitable sources of supply such as the spools 49 and pass over and down between the wheels 34. The rims 36, which may be knurled or corrugated, press the edges of one web against the edges of the other web. Between the rims 36 there are one or more cavities extending in from the surface of the wheels. In the case of each wheel, surface portions 42 extend from one rim to the other and separate one cavity from the next. The wheels are adjusted so that as they revolve, the surface portions 42 of one wheel meet the surface portions 42 of the other wheel. Thus, with the turning 10 of the wheels, successive chambers are presented into which successive bags drop. The bags do not touch the wheels because the webs are passing over the wheels. The bags are accordingly caught between the webs, the longitudinal edges of which are being sealed by the action of the wheel rims. The wheel chambers permit each bag to pass down between the wheels. Beneath the bag, as it passes down, the webs have been sealed by the pressure of the surfaces 25 42. As each bag leaves the wheels, the webs are sealed behind the bag and its tag by the next contacting surface 42. Shearing means 44 cut the webs between successive bags which are then free to drop onto a finally disposing conveyor 46.

30 The sealing of the webs may be facilitated by heat which can be supplied to the wheels 34. The belts 30 may be driven from a source (not shown) by the rotation of pulleys 110 over which the belts pass.

35 Any suitable means may be used for coordinating and synchronizing the motion of conveyor 10, the opening of the forks 24, the motion of the propelling finger 32, the rotation of the wheels 34, and the shearing action of the means 40 44. Thus, a cam 112 on a mutual shaft 114 with pulley 110 may actuate a roller 116 to operate linkages 118 and 119 which cause the periodic and sudden motion of rotation of the rods 26. As shown, linkage 119 is pivoted on pivot 120 45 attached to hopper 22. One of the rods 26 is attached to linkage 119. The other rod 26 is attached to a link 121 pivoted about pivot 123 on the hopper. Cam surfaces 125 on linkages 119 and links 123 cause the latter to rotate when the former rotate. This rotation of the bars and their tines about pivots 120 and 123 causes the distal ends of the tines in one set to separate from the distal ends of the tines in the other set. A cam 122 on one of the shafts 114 gives 50 an intermittent motion to roller 124 which is attached to the pivoted arm 126. A link 128 from the end of that arm is pivotally connected to finger 32. The latter is itself pivoted about a horizontal shaft 130. The intermittent motion 55 of the link causes the finger to strike intermittently in between the belts 30 to deliver a bag down against its tag and the webs 38.

The operation of the device has been described in connection with its parts.

60 Since certain changes may be made in the above construction and different embodiments of the invention could be made without departing from the scope thereof, it is intended that all matter contained in the above description or 70 shown in the accompanying drawings shall be interpreted as illustrative and not in a limiting sense.

It is also to be understood that the following claims are intended to cover all the generic and 75 specific features of the invention herein de-

scribed, and all statements of the scope of the invention which, as a matter of language, might be said to fall therebetween.

Having described my invention, what I claim as new and desire to secure by Letters Patent is: 5

1. In combination, grille means for receiving in proximity thereto a tag and an object to which the tag is connected and for permitting the tag to be pulled through said grille means and become spaced from the object, means causing the 10 spaced object and tag to approach a point, and propelling means for moving the object into proximity with the tag at least by the time the object and the tag reach said point.

2. In combination, grille means for receiving 15 in proximity thereto a tag and an object to which the tag is connected and for temporarily, at least, preventing the object from passing through said grille means and for permitting the tag to be pulled through said grille means and become 20 spaced from the object, means causing the spaced object and tag to approach a point, and propelling means for moving the object into proximity with the tag at least by the time the object and the tag reach said point. 25

3. In combination, grille means for receiving in proximity thereto a tag and an object to which the tag is connected and for permitting the tag to be pulled through said grille means and become 30 spaced from the object, means for permitting a force to cause the spaced object and tag to approach a point, and propelling means for moving the object into proximity with the tag at least by the time the object and the tag reach said point. 35

4. In combination, grille means for receiving in proximity thereto a tag and an object to which the tag is connected and for permitting the tag to be pulled through said grille means and become 40 spaced from the object, means for permitting gravity to cause the spaced object and tag to approach a point, and propelling means for moving the object into proximity with the tag at least by the time the object and the tag reach said point. 45

5. In combination, grille means for receiving in proximity thereto a tag and an object to which the tag is connected and for permitting the tag to be pulled through said grille means and become 50 spaced from the object, means withdrawing said grille means from the path of the object and tag whereby they may approach a point, and propelling means for moving the object into proximity with the tag at least by the time the object and the tag reach said point. 55

6. In combination, grille means for receiving in proximity thereto a tag and an object to which the tag is connected and for permitting the tag to be pulled through said grille means and become 60 spaced from the object, means withdrawing said grille means from the path of the object and tag whereby they may approach a point, means for controlling the passage of the object and tag for at least a portion of the distance between said grille means and said point, and propelling means for moving the object into proximity with the tag at least by the time the object and the tag reach said point. 65

7. In combination, grille means for receiving in proximity thereto a tag and an object to which the tag is connected and for permitting the tag to be pulled through said grille means and become 70 spaced from the object, means withdrawing said grille means from the path of the object and tag whereby they may approach a point, 75

- means for controlling the passage of the object and tag for at least a portion of the distance between said grille means and said point, and propelling means for moving the object into proximity with the tag at least by the time the object and the tag reach said point and permitting the continued spaced relation of the object and tag.
8. In combination, grille means for receiving in proximity thereto a tag and an object to which the tag is connected and for permitting the tag to be pulled through said grille means and become spaced from the object, means withdrawing said grille means from the path of the object and tag whereby they may approach a point, means for controlling the passage of the object and tag for at least a portion of the distance between said grille means and said point and comprising an endless belt, and propelling means for moving the object into proximity with the tag at least by the time the object and the tag reach said point.
9. In combination, grille means for receiving in proximity thereto a tag and an object to which the tag is connected and for permitting the tag to be pulled through said grille means and become spaced from the object, means withdrawing said grille means from the path of the object and tag whereby they may approach a point, means for controlling the passage of the object and tag for at least a portion of the distance between said grille means and said point, propelling means for moving the object into proximity with the tag at least by the time the object and the tag reach said point, and means for operating said propelling means at a predetermined time after said grille means has been withdrawn.
10. In combination, grille means for receiving in proximity thereto a tag and an object to which
- the tag is connected and for permitting the tag to be pulled through said grille means and become spaced from the object, means withdrawing said grille means from the path of the object and tag whereby they may approach a point, means for controlling the passage of the object and tag for at least a portion of the distance between said grille means and said point, propelling means for moving the object into proximity with the tag at least by the time the object and the tag reach said point, means for operating said propelling means at a predetermined time after said grille means has been withdrawn, and means for repositioning said grille means and said propelling means whereby they may operate similarly upon another object and tag.
11. In combination, grille means for receiving in proximity thereto a tag and an object to which the tag is connected and for permitting the tag to be pulled through said grille means and become spaced from the object, means withdrawing said grille means from the path of the object and tag whereby they may approach a point, means for controlling the passage of the object and tag for at least a portion of the distance between said grille means and said point, propelling means for moving the object into proximity with the tag at least by the time the object and the tag reach said point, means for operating said propelling means at a predetermined time after said grille means has been withdrawn, means for repositioning said grille means and said propelling means whereby they may operate similarly upon another object and tag, and means for successively delivering units, each comprising an object and a tag, at predetermined intervals to said grille means.

JAY TAMASSY.
